CLAIM

The ornamental design for a mock engine block as shown and described.

DESCRIPTION

FIG. 1 is a perspective view of the mock engine block.

FIG. 2 is a left view of the mock engine block.

FIG. 3 is a right view of the mock engine block.

FIG. 4 is a top view of the mock engine block.

FIG. 5 is bottom view of the mock engine block.

FIG. 6 is a front view of the mock engine block; and,

FIG. 7 is a back view of the mock engine block.
